UNITED STATES PATENT OFFICE.

ERNEST K. READ, OF WILKINSBURG, PENNSYLVANIA, ASSIGNOR TO WESTINGHOUSE ELECTRIC & MANUFACTURING COMPANY, A CORPORATION OF PENNSYLVANIA.

CHANGE-OVER SWITCH.

Application filed September 24, 1920. Serial No. 412,543.

To all whom it may concern:

Be it known that I, ERNEST K. READ, a citizen of the United States, and a resident of Wilkinsburg, in the county of Allegheny 5 and State of Pennsylvania, have invented a new and useful Improvement in Change-Over Switches, of which the following is a specification.

My invention relates to change-over 10 switches and particularly to switches used in transferring the load circuit from one supply circuit to another in the event of a reduction in voltage in one of the circuits.

In certain lighting systems, such, for example, as are employed in subways, it is essential that the subways be lighted at all times regardless of the failure of the circuit supplying the trains with current for power and lighting purposes. An auxiliary power 20 line, receiving its current from a different source than the main power line, is associated with the electrical system, for the purpose of supplying current for lighting and other purposes in the emergency of a 25 failure of the main supply circuit.

One object of my invention is to provide a switch mechanism that is responsive to variations in the voltage in the main supply circuit, and that will, upon a predetermined 30 reduction in the voltage in the main supply circuit, open a switch connecting that circuit with the load circuit and close a switch closing the auxiliary circuit with the load circuit and transfer the load circuit back to 35 its original supply circuit when the voltage in that circuit returns to normal.

Another object of my invention is to provide a switch mechanism having the above characteristics wherein the switches controlling the supply circuits are so connected 40 that one switch cannot be closed before the other is fully opened.

A further object of my invention is to provide a switch mechanism of the character described wherein the switches are operated with a snap action.

These and other objects which will be made apparent throughout the further description of the invention are attained by 50 means of the switch apparatus herein described and illustrated in the accompanying drawings, wherein:

Figure 1 is a front elevational view of one

form of the switch mechanism embodying my invention. 55

Fig. 2 is a bottom view of the switch-operating mechanism shown in Fig. 1.

Fig. 3 is a bottom view of a modified form of switch-operating mechanism.

Fig. 4 is an end elevational view of the 60 switch mechanism shown in Fig. 1.

Referring to the drawings, the apparatus includes a panel or base 6 upon which is mounted a pair of movable switch members 7 and 8. The switch members illustrated in 65 Figs. 1 and 4 are of a standard type well known in the art, which consists generally of a pair of switch arms 9 and 10 that are pivoted upon stationary terminal-jaw members 11 and 12. The arms 9 and 10 are provided with yieldingly mounted contact members 13 and 14, respectively, that engage contact members 15 and 16, which are connected, through the usual blow-out coils 17 and 18, to the terminals 19 and 20 (the former of which is shown in Fig. 4) that are 70 connected to the load circuit. 75

Current from the main supply circuit and from the auxiliary supply circuit flows 80 through the switch members 7 and 8 from terminals 21 and 22 (the former of which is shown in Fig. 4). When the switch member 7 is in closed position, the main supply circuit is connected with the load circuit and, when the switch member 8 is in closed position, the auxiliary supply circuit is 85 connected with the load circuit.

Referring to Figs. 1 and 2 wherein one form of switch-operating mechanism is illustrated, the operating mechanism shown includes a pair of overlapped operating levers 23 and 24 that are pivoted adjacent their over-lapped ends by means of a shaft 25 that is mounted upon a frame 26 which surrounds an operating coil or solenoid 26'. The outer ends of the levers 23 and 24 are pivotally connected to the switch arms 7 and 8, respectively, by means of a universal-joint connection including adjustable rods 27 and 28. The ends of the rods are threaded and are provided with nuts 29 whereby the positions of the switches 7 and 8 relative to their respective operating levers may be adjusted. The lever 23, for operating the main supply circuit, is normally 100 held in closed position by a helical spring 105

30 that is attached, at one end, to the lever 23 and, at the other end, to a bracket 31 that is secured to the frame 26. The spring 32, attached, at one end, to the overlapped end 33 of the lever 24, and, at the other end, to the bracket 31, normally tends to move the switch arm 8 to open position. The lever 24 is moved to closed position against the tension of the springs 30 and 32 by means of a core member 34 that is pivoted, at the upper end, to the lever 24 at a point between the pivot shaft 25 and the outer end of the lever. The core member extends into the coil and causes the lever 24 to move downward to the closed position shown in Fig. 2, when the coil is energized, preferably by current supplied from the auxiliary supply circuit.

The overlapped end 35 of the member 23 extends above the lever 24 and is provided with a shoe 36 that is adapted to be engaged by a latch member 37 which is pivoted to the frame 26 by means of the pivot pin 38. The latch is normally held in a position in which it may engage the shoe 36 by means of the helical spring 39 disposed between the lower extremity of the latch and the frame 26. When the lever 24 is moved downward to closed position in response to the energization of the operating coil 26', the end 33 of the lever engages the web 40 carried by the lever 23 and causes opening movement of that lever and the attached switch arm 7. The pivot shaft 25 is so located that the switch arm 7 is entirely withdrawn from the contact member 15 before the switch arm 8 has moved the contact member 14 into engagement with the stationary contact member 16.

When the switch arm 8 has been moved to closed position, the shoe 36 of the lever 23 is engaged by the latch 37 and is thereby releasably retained in open position. The lever 24 is provided with an adjustable screw 41 which may be so adjusted that, when the lever 24 is moved a sufficient distance to cause the switch 8 to open sufficiently to extinguish the spark incident to the separation of the switch from its contact, the screw 41 engages a projection 42, carried upon the inner edge of the latch 37, and trips the latch 37 out of engagement with the shoe 36. The spring 30 then closes the switch arm 7 with a snap action through the medium of the lever 23.

It will be apparent from the foregoing, that normally, the spring 30 retains the switch arm 7 in closed position and the switch arm 8 in open position by reason of the engagement of the web 40 carried by the lever 23, with the end 33 of the lever 24. Energization of the coil 26' causes the switch 7 to be quickly opened and the switch 8 to be subsequently closed.

In normal operation, the load circuit is sup-

plied with current from the main supply circuit through the switch 7. A relay 43 (Fig. 1) that is permanently connected with the live side of the switch 7, controls the current to the operating coil 26' which is connected to the live side of the switch 8 and receives current from the auxiliary supply circuit. The relay may be adjusted to close the circuit through the operating coil, upon a predetermined drop of voltage in the main supply circuit and will effect the transfer of current supply to the load circuit when the voltage in the main supply circuit falls below the predetermined amount. When the voltage in the main supply circuit is restored to normal, the current through the operating coil is interrupted by the action of the relay, which opens the circuit when the voltage in the main supply circuit is restored and the switch 7 is again closed after the switch is opened.

In Fig. 3, I have shown a modified form of switch-operating mechanism wherein both the switch controlling the main supply circuit and the switch controlling the auxiliary supply circuit are held wide open until the closed switch has been moved to open position.

In this construction the levers 23 and 24 are similar to the corresponding levers employed in the construction illustrated in Fig. 2, except that the lever 24 is provided with an extension 45 similar to the extension 35 of the lever 24 (shown in Fig. 2) and the screw 41 carried by the lever 24 is mounted upon an intermediate rocking lever 46 that is mounted between the levers 23 and 24. This rocking lever is pivoted upon the shaft 25 upon which the levers 23 and 24 are also pivotally mounted, and is provided with laterally-extending lugs 47 and 48 that engage the under edges of the levers 23 and 24, respectively.

As shown in Fig. 3, the elements of the mechanism are in the position occupied when the auxiliary supply switch is closed. At this time, the operating coil 26' is energized, and the rocking lever is held in the position shown by means of the core 34 that is attached thereto at a point on the right side of a pivot shaft 25. The lever 24 is held in closed position by a spring 49. At such time, the voltage in the main supply circuit is below the predetermined voltage and the relay has, therefore, closed the circuit through the operating coil 26'.

When the voltage in the main supply circuit has returned to normal the relay 43 is actuated and opens the circuit through the operating coil. The moment the operating coil is de-energized, the spring 50, that is connected to the left-hand end of the rocking lever 46, turns the rocking lever counter-clockwise to move the right-hand end thereof upward. The lug 48, carried by the rock-

ing lever, engages the under side of the lever 24, and, because the spring 50 is stronger than the spring 49, moves the said lever to open position with a snap action, 5 carrying with it the switch arm 8 controlling the auxiliary supply circuit.

The screw 41 engages the extension 42 carried upon the latch 37 after the lever 24 has been moved to open position, to trip the 10 latch 37 which has been holding the lever 23 in open position against the tension of the spring 30. The spring 30 causes the switch 7, to which the lever 23 is attached, to close with a snap action. The lever 24 15 is, at this time, held in open position by the latch 51 which engages a shoe 52 carried by the lever extension 45.

When the relay 43 again closes the circuit through the operating coil, in response to 20 a drop in voltage in the main supply circuit, the rocking lever is turned in a clockwise direction by the core 34. The lug 47 engages the under side of the lever 23 to cause it to be moved to open position with a snap 25 action. When the rocking lever 46 has moved the lever 23 to wide-open position, an adjustable screw 53 carried by the rocking lever trips the latch 51 which permits the lever 24 to be moved to closed position, 30 with a snap action, by the spring 49.

From the foregoing, it will be apparent that the switch mechanism, above described, transfers the load circuit to the auxiliary supply circuit in the event of a predetermined reduction in the voltage in the main supply circuit. The mechanism is such that the switch controlling the main supply circuit is moved to full-open position wherein the spark is extinguished before the switch 35 controlling the auxiliary circuit is moved to closed position. When the voltage in the main supply circuit is restored to normal, the switch controlling the auxiliary supply circuit is moved to full-open position 40 wherein the spark is extinguished before the switch controlling the main supply circuit is moved into contact with the stationary contact members. It is, therefore, impossible to connect both circuits with the load 45 circuit at the same time.

While I have described and illustrated but two embodiments of my invention, it will be apparent to those skilled in the art that various changes, modifications, substitutions, additions and omissions may be made 50 in the apparatus described without departing from the spirit and scope thereof, as set forth by the appended claims.

I claim as my invention:

60 1. Switch mechanism comprising a pair of separate switch members, means normally tending to move the switch members to closed position, latch means for holding one of the switch members in open position and 65 means for tripping the latch to release the

said switch member after the other switch member has been moved to open position.

2. Switch mechanism comprising a pair of separate switch members, yielding means normally tending to hold one of the switch members in closed position, latch means for retaining the said switch member in open position, yielding means normally tending to hold the other switch member open, means for moving the last said switch member to closed position, and for releasably retaining it in closed position, and means for tripping the said latch means to release the first said switch member after the last said member has moved to open position. 75

3. Switch mechanism comprising a pair of separate switch members movable to open and to closed position, separate latch means for releasably latching the said switch members in open position, yielding means normally tending to move the said members to closed position, and an operating member 80 for moving a closed switch member to open position and for tripping a latch holding the other member in open position after the 85 closed switch has been moved a predetermined distance.

4. Switch mechanism comprising a pair of separate switch members movable to open and to closed position, means for releasably latching one of the said switch members in open position, yielding means normally tending to move the said members to closed position, a latch for the other switch member, an operating member movable with respect to the said first latch and engaging a closed switch member for moving said switch member to open position and for engaging and tripping the second latch holding the other member in open position, 95 after the closed switch has been moved a predetermined distance, and means carried by the said operating member for varying the degree of relative movement between the member and the said first latch. 100

5. Switch mechanism comprising a pair of separate switch members movable to open and to closed position, a pair of pivotally-connected operating levers for the switch members movable to open and to closed position, having overlapping ends, latch members engaging the overlapped ends of the switch members for releasably retaining the levers in open position, and means for moving a closed lever to open position adapted to trip the latch retaining the other lever to release the switch after the closed lever has been moved to open position. 115

6. A change-over switch comprising a switch for connecting a load circuit with a supply circuit, a switch for connecting the said load circuit with an auxiliary supply circuit, yielding means for normally holding the first switch in closed position and the second switch in open position, means for 120

releasably latching the first switch in open position, electro-magnetic means for closing the second switch and opening the first switch, and means for moving the second switch to open position independently of the first switch, adapted to release the said latch to permit closing movement of the

first switch after the second switch has moved a predetermined distance.

In testimony whereof, I have hereunto 10
subscribed my name this 7th day of Septem-
ber, 1920.

ERNEST K. READ.
